UNITED STATES PATENT OFFICE

HENRY M. LUNDY, OF SPOKANE, WASHINGTON

GRAB DEVICE

Application filed May 13, 1930. Serial No. 451,972.

My invention relates to grab devices and more particularly to a device comprising a grab member mounted on a vehicle, such as a locomotive, train caboose or the like, and also comprising a stationary member secured to the ground whereby the vehicle or train, while running at high speed, may seize a holder member that is detachably mounted on the stationary member. The primary object 10 of the invention is the delivery of orders or messages carried by the holder member to the engineer or train crew and embodies means for delivery of such messages to one or more locomotives or vehicles and to the 15 caboose of the train. Further objects of the invention are to provide novel release devices for detachably retaining the holder member, novel grab means, and other novel details of construction and arrangement.

20 With the above and other objects in view which will appear as the description proceeds, the invention consists of the novel construction, adaptation, combination and arrangement of parts hereinafter described and 25 claimed. These objects are accomplished by devices illustrated in the accompanying drawings; wherein:—

Figure 1 is a view in elevation of the complete device and showing a portion of a locomotive cab with its grab member disposed in cooperative relation with the holder member that is detachably mounted on the stationary release member;

Fig. 2 is an enlarged detail view in perspective showing the outer end portion of the grab member in cooperative relation with the holder member;

Fig. 3 is a detail view in vertical section showing the assembly of one of the release devices which devices detachably retain the holder member;

Fig. 4 is a fragmentary view in elevation showing the means for yieldingly retaining 45 the pivotal arms of the stationary release member in the inoperative position;

Fig. 5 is a detail plan view of the bracket support for the grab member;

Fig. 6 is a fragmentary detail view, partly 50 in elevation and partly in section, showing

the adjustable connection between the grab arm and the grab frame;

Fig. 7 is a detail view in perspective of the 55 sliding sleeve and retainer means for one of the release devices; and

Fig. 8 is a detail view in perspective showing the cylindrical housing for the sleeve and spring of one of the release devices.

Referring to the drawings throughout which like reference numerals indicate like parts and more particularly to Fig. 1, the numeral 5 designates the standard or post of the stationary portion of the device whose base is ordinarily fixed to a concrete pier 6 on the ground. A lower arm 7 is pivoted at 65 8 to the standard and an upper arm 9 is pivoted at 10 to said standard. The outer end of the lower arm is provided with a single pair of spaced apart release devices each designated as a whole by the numeral 11 and 70 which are mounted on a bracket 12, and the upper arm is provided with a double pair of such release devices mounted in spaced relation on a double bracket 13. The upper arm is therefore adapted to release two messages, such as for instance, to two locomotives pulling one train of coaches and known as a "double header", while the lower arm is adapted to release one message, such as for instance, to the caboose of the train. 75

The upper arm 9 is provided with a counter-weight 14 that is adapted to retain said arm in the normally horizontal or operative position against a stop bracket 15 secured to the standard 5. Said arm is also provided with a pull cord 16 passing downwardly over a sheave or guide 17 fixed to the standard and is provided with a handle 18 at its lower end whereby the arm may be pulled downwardly to the inoperative position shown in dotted lines in Fig. 1. The means for retaining said arm in the inoperative position, as shown in detail in Fig. 4, 90 comprises a bracket 19 offset from the standard and having a spring clip 20 secured to its outer flanged end. A tongue 21 connected to said arm and having a contracted middle portion is adapted to project between the jaws of said spring, in the downward position, the tension of whose outer contracted

100

end portions yieldingly retains the tongue in the grasp of the spring jaws. The tension of said spring jaws may be regulated by a bolt 22 as will be understood.

5 The lower arm 7 is provided with a cord 23 secured thereto and passing upwardly over a sheave 24. Said cord is provided with a handle 25 whereby the arm may be pulled upwardly to the dotted position shown in 19 Fig. 1. In the operative or horizontal position said arm rests by its own weight on a bracket arm 26 and is provided with a tongue 27 that is adapted to be held by a spring retaining means 28 when the arm is in the upward or inoperative position. Said spring retaining means is identical with that previously described for the upper arm 9 and no further description is deemed necessary. A step ladder 29 provides means whereby an 23 operator may reach the upper and lower arms for manipulation of the releasing devices.

In Fig. 3 of the drawings one of the release devices 11 is shown in detail, and, as all six of said devices are identical, a description 23 of only one is considered necessary. Said devices comprise a cylindrical housing 30, shown in detail in Fig. 8, having a closed end wall 31 and a slot 32 extending the full length thereof. The open end portion of said housing is secured by a pin 33 into a cup 34 formed on a deflected end portion of the brackets 12 or 13. Said housing is disposed in the vertical position when the arm 7 or 9 is in the horizontal or operative position and in this position its slot is on the outer side of the housing. A sleeve member 35, shown in detail in Fig. 7, is slidably mounted within said housing and is provided with a closed end 36. Said sleeve has a relatively narrow short arm 37 extending at right angles from its open end portion and a relatively wide lip 38, formed on the end of said arm, is disposed in parallel relation with said sleeve.

In the installed position of the sleeve 35 its closed end 36 is disposed within the bracket cup 34 and its short arm 37 projects slidably through the slot 32 of the cylindrical housing 30. A coiled spring 39 has one of its ends bearing against the closed end of said sleeve and its other end bearing against the closed wall 31 of said cylindrical housing. Thus, in the expanded position, said spring normally retains the sleeve fully within the bracket cup portion of the housing with its short arm bearing against the open end edge portion of the cup as clearly shown in Fig. 3 of the drawings.

In each cooperative pair of release devices 69 the sleeves 35 are oppositely arranged so that their springs 39 hold them away from each other in a relatively expanded position and they may be contracted or drawn together by pressing their lips 38 toward each other whereby their arms 37 will be slidably moved in the housing slots 32 to the dotted

position shown in Fig. 3. In this position the two hooked ends 40 of an arm 41, that is secured to the rectangular frame 42 of the holder or message carrier member, may be caught over their respective lips and when 70 the pressure on their springs is released they will expansively retain said holder or carrier member in place and in readiness to be caught by the grab member. As shown in Fig. 2, a leaf spring 43, secured to the underside of the rectangular carrier frame, provides means for holding the paper or envelope containing the message that is to be delivered to the train crew. 75

The grab member comprises a bracket 44 that is secured to the vehicle, train cab or coach at the proper elevation. Said bracket is provided with an upstanding pin 45 and a pair of spaced upstanding guide lugs 46 as most clearly shown in Fig. 5. A grab arm 47 fits between said lugs and is provided with an end eye 48 which fits over said pin whereby the arm is detachably retained in the proper horizontal operative position. Said grab arm has a U-shaped grab frame 49 yieldingly held in a slot 50 by a bolt 51 whose extended threaded end portion has a coiled spring 52 thereon which is tensioned by a nut 53 as shown in detail in Fig. 6. This arrangement provides means whereby said frame may be slipped from its slot, turned over and allowed to snap back into its slot. Thus it will be seen that the frame may be reversed and the entire grab member detached from its bracket and installed on a corresponding bracket on the other side of the cab, coach or other vehicle. 90

The U-shaped grab frame 49 has a locking bar 54 pivotally secured at 55 to the outer end of its upper arm and the lower end portion of said bar is arranged to normally rest against the outer end of a slot 56 in the outer end portion of the lower arm of said frame. Assuming that the hooks 40 of the holder member are caught over and under the lips 38 respectively of the releasing device as shown in the lower pair of releasing devices in Fig. 1, when said locking bar strikes the upper member of the rectangular holder frame 42 said bar will pivotally swing back free of its slot allowing the frame member to pass inside of the U-shaped grab frame as clearly shown in Fig. 2. The locking bar will immediately fall back to its normally locked position within its slot thus preventing the holder frame from escape. The grab arm 47 will then strike both end members of the holder frame at the same time, knocking said frame from its hold by the hereinbefore described releasing devices and carrying it along with the locomotive cab, caboose or other vehicle with its attached message to the train crew or operators of the vehicle. 110

Having thus described my invention, it 125

being understood that minor changes may be resorted to in its construction and arrangement without departing from the scope and spirit of the invention, what I claim and desire to secure by Letters Patent of the United States is:—

1. A releasing device comprising a cup member, a cylindrical housing connected to the cup and having a slot therein, a sleeve 10 member slidably mounted within the cylindrical housing, a short arm for said sleeve slidably disposed through the housing slot, a lip member for the arm, and a spring arranged to yieldingly retain the sleeve in one 15 end portion of the cylindrical housing.
2. A grab device having in combination a grab arm detachably secured to a vehicle at right angles thereto, means whereby said grab arm may be reversed to the opposite 20 side of the vehicle, a U-shaped grab frame detachably secured to said arm, spring and pivot connecting means whereby said frame may be reversed by turning same over without disconnecting same from the arm, a locking 25 bar pivotally connected to the upper arm of said grab frame, a rectangular message carrying member, a leaf spring message holder for the message carrying member, hooked arms for said message carrying member, a 30 stationary release member mounted on the ground, a plurality of releasing devices for said release member, the hooked arms for the message carrying member being adapted to be detachably connected to said releasing 35 devices in the path of the grab frame, the locking bar of the grab frame being arranged to pivotally move when contacted by the message carrying member whereby said carrying member is locked into the grab frame, 40 and the message carrying member being adapted to be dislodged from the release member upon contact by the grab arm.

In testimony whereof I affix my signature.
HENRY M. LUNDY.
